UNITED STATES PATENT OFFICE.

RAY P. SAFFOLD, OF SAN FRANCISCO, CALIFORNIA.

SHIRT.

1,169,515.

Specification of Letters Patent. Patented Jan. 25, 1916.

Application filed October 28, 1914. Serial No. 869,042.

To all whom it may concern:

Be it known that I, RAY P. SAFFOLD, a citizen of the United States, residing at San Francisco, in the county of San Francisco and State of California, have invented certain new and useful Improvements in Shirts; and I do hereby declare the following to be a full, clear, and exact description of the invention, such as will enable others skilled in the art to which it appertains to make and use the same.

My invention relates to improvements in shirts, shirt waists and undershirts, and it consists in the novel forms and constructions herein shown and described.

An object of my invention is to provide an improved shirt, shirtwaist or undershirt, adapted to prevent irritating pressure upon the spinal column and larynx, and to avoid the inconvenience of a double thickness of collar band at the front or back opening of said shirt, waist or undershirt.

A further object of my invention is to provide an improved garment adapted to prevent disagreeable rumpling or humping just below the neck band at the back.

A further object of my invention is to provide an improved garment which will eliminate the unnecessary wad or roll formed around the waist and hips of a wearer by previous constructions.

Further objects of my invention are to allow the use of smaller and larger collars on the same shirt; to employ the same kind of collar band solid in front on dress and plain shirts; to employ a pair of small buttons in the back and front of the collar band instead of single buttons as is now usual; and to prevent sagging and pinching in front of a dress shirt by using a collar band that is not divided in front.

In the accompanying drawings, forming a part of this application, in which similar reference symbols indicate corresponding parts in the several views, Figure 1 is a fragmentary front view of a shirt or garment illustrating one embodiment of my invention; Fig. 2 is a rear view of the garment shown in Fig. 1; Fig. 3 shows a collar attached to the usual central front button hole of the collar band of a garment; Fig. 4 is a fragmentary view showing the relative positions of the rear ends of the neck band; Fig. 5 is a perspective view showing the collar attached to pairs of buttons occupying laterally spaced auxiliary button holes according

to my improved construction; Fig. 6 is a fragmentary perspective view showing the relative positions of the rear ends of the neck band before the collar is attached thereto, as in Fig. 5, and Fig. 7 is a view similar to Fig. 6 with the ends of the neck band drawn apart.

Referring to the drawings, 1 indicates the front of a dress shirt illustrating one embodiment of my invention which is open at 2 in the usual manner, and also preferably provided with an opening 3 in its back 4. The shirt is provided with a neck band 5 which is separated only at the back opening 3 of the shirt, and which is continuous in front to provide an attachment for insuring a smooth set of the open, or split, shirt bosom. In order to prevent troublesome rumpling or humping of the shirt just below the neck band at the back, I provide the edges of the back opening 3 with triangular cut out portions 6, or other suitable incisions. As shown, especially in Fig. 2, the garment is provided with a back tail 7 which terminates a slight distance below the waist line 8, and with a central front tail 9 of less width than the body of the garment. This provides a novel and very comfortable construction which eliminates the unnecessary wad or roll formed around the waist or hips of a wearer in previous constructions.

The front of the neck band 5 is shown provided with a central button hole 10 for attaching a collar 12 by the usual long shank collar button 50 as shown in Fig. 3, and with a pair of auxiliary button holes 11 spaced at the respective sides thereof for attaching the collar by two short collar buttons 51 and 52 as shown in Fig. 5. The rear of the collar is attached by a pair of buttons 58 and 60, as will be readily understood. By this improved construction, the auxiliary buttons 51 and 52 avoid all irritating pressure, enable the front edges of the collar 12 to be spaced apart for comfort, while the rear buttons 58 and 60 eliminate the inconvenience and nuisance of the overlapping or double thickness of the collar in the back, all as will be clear from the drawings.

The rear ends 13 and 14 of the neck band 5 are provided with lateral button holes 15 and 16 respectively, and a tab 17 provided with a central button hole 18 extends from the band end 13; loops, and additional tabs 19 and 20 extend from the tab 17 and the band end 14 respectively as shown. In this

improved construction, the loop or tab 19 is placed over the lateral button hole 16, as shown in Fig. 6, for connecting the ends of the neck band by a collar button 21 when the back of the collar 12 is attached by the collar buttons 21 and 22.

The back of the collar 12 is further provided with a pair of auxiliary button holes at the sides of the usual central button hole 10 for receiving the collar buttons 21 and 22. This prevents irritating pressure of the collar buttons 21 and 22 against the spinal column and avoids the inconvenience of a double thickness of collar band at the back. 15 If it is desired to attach the back of the collar 12 by a single button in the usual manner, the loop or tab 20 is placed over the button 55 in the central button hole 18 in the tab 17, as shown in Fig. 4. If no collar 20 is to be worn, a button can be inserted through the superposed loops 19 and 20 for attaching the neck band loosely and comfortably about the neck; or tabs 19 and 20 can be made to register with buttonholes 15 and 16.

While I have illustrated my invention to apply to a dress shirt, it will be obvious that it is equally applicable to the usual stiff shirts which open only at the back, and to 30 coat shirts which open only in the front. When applied to coat shirts, the button holes 10 and 11 are placed at the back of the collar band, and the tab 17 and loops or tabs 19 and 20 are provided at the front ends of 35 the collar band. My invention is equally adaptable to tailored shirt-waists which are worn with detachable collars and to undershirts by omitting the tails 7 and 9.

It is obvious that those skilled in the art 40 may vary the details of construction without departing from the spirit of my invention, and, therefore, I do not wish to be limited to the above disclosure except as required by the claims.

What I claim is:—

1. A garment open front and back having a neck band continuous at the front and provided with the usual central front button hole for attaching a collar and with a pair of auxiliary front button holes spaced at 50 the respective sides of the central button hole for attachment to a collar independently of said central hole.

2. A garment open front and back having a neck band provided with the usual central 55 button holes at the front and back and with auxiliary button holes spaced at each side of the said central button holes for attachment to a collar independently of said central holes.

3. A garment having a neck band continuous at the front and provided with the usual central button hole at the back and with a pair of auxiliary button holes spaced at 60 the respective sides of the central button hole, and a collar provided with a central button hole at the back, and with a pair of auxiliary button holes spaced similarly to said pair of auxiliary holes of the neck band.

4. A garment open at both front and back 70 and having a neck band continuous in front and separated only at the back opening, said neck band being provided with the usual central front and back button holes and with a pair of button holes spaced at each side of 75 the said usual central button holes for attaching the collar.

5. A garment having a continuous collar band at the front but opening at the front and back and provided with a triangular 80 cut in each of the edges of the back opening in proximity to the neck band.

In testimony whereof, I affix my signature, in presence of two witnesses.

RAY P. SAFFOLD.
